APPARATUS FOR CASTING DENTAL RESTORATIONS

Elliott M. Feinberg, Woodmere, N. Y.

Application February 15, 1941, Serial No. 379,027

10 Claims. (Cl. 18—5.7)

The invention relates to a machine for use in making castings of plastic and has particular application in the casting of dental restorations, that is, in restoring lost tooth structure, using plastic as the casting material. Using the machine to be described herein, a bridge, an artificial tooth or part thereof, such as an inlay crown and the like, plates, and other dental structures may be formed.

There are at present two plastics, namely, methacrylate and polystyrene, which have been especially satisfactory for use for dental restorations. Other plastics, such as interpolymers, also have desirable characteristics. These plastics have many advantages such as being highly resistant to acids, alkalies, oils, alcohols and water. The natural translucency and clear water color of the plastics enable them to be colored or tinted any shade that may be desirable for use in denture service. The technique used in forming the mold for casting a dental restoration does not differ, or does not differ materially, from that now used by dental technicians in making molds for metal castings.

It is an object of the invention to devise a new and novel apparatus which is particularly suited for casting dental restorations using a plastic as the casting material.

Another object of the invention is to construct an apparatus for casting dental restorations, using plastic as the casting material, in which a plastic receiving chamber is carried by or associated with the flask. In the embodiment particularly illustrated, the chamber is formed in the investment. The apparatus also retains pressure on the plastic during the setting or curing thereof. Since the plastic takes several minutes or more to set, the pressure must be retained thereupon for a substantial period of time in order to assure that the casting does not contract or does not contract to an extent to be detrimental during the setting or curing of the plastic.

Another object is to provide a new and novel combination of flask, investment and apparatus or machine for casting dental restorations using plastic as the casting material.

Other objects of the invention will be more apparent from the following description taken in connection with the accompanying drawing, illustrating a preferred embodiment of the casting apparatus and a device used to form a plastic receiving chamber in the investment, in which:

Figure 1 is a front elevation of an apparatus for casting dental restorations using plastic as the casting material. This figure includes a long-

itudinal section through a flask in position within the apparatus and with the parts in the position assumed when forcing plastic into the mold within the flask. Other sections show other details of construction.

Figure 2 is a section, taken on line 2—2 of Figure 1, showing the platform construction of the apparatus and the manner in which it is guided by side members upon the frame of the apparatus.

Figure 3 is a section through a unitary form of flask with the cylinder forming member in position thereupon and carrying a wax pattern which forms the mold in the investment.

Figure 4 is a plan view of the chamber forming member.

Figure 5 shows a pattern carried upon a sprue pin which is ready for mounting upon the chamber forming member of Figure 4.

Figure 6 is a section through the piston or plunger of the apparatus showing the manner in which the piston or plunger is mounted for free rotation upon the end of the propelling or pressure screw.

25 The plastic used for making dental restorations should be in a soft, but viscous state, that is about the consistency of putty or a thick paste. Plastic in this condition may be obtained or prepared in two ways. Powdered or granulated plastic in its cured or polymeric form is mixed with a portion of the plastic in liquid or monomeric form in a manner known to the dental technician in preparing plastic to be used for forming dental plates. The viscous plastic may be obtained also by using polymeric plastic in powdered, granular or biscuit form and heating it until it has the proper viscous consistency. The plastic, of course, will be previously tinted or colored to the desired shade.

40 The investment for the casting may be formed in the customary manner, using known materials. A wax pattern 10 is formed in a known manner, after which it is mounted upon a sprue pin 11 or the wax pattern may be formed upon the end of the sprue pin so that it is partially embedded therein, as desired. A chamber forming member 12 has a chamber or cavity former 13 carried thereby and one or more shoulders 14 and 15 for aligning the chamber former with a flask, each shoulder being adapted for a different size of flask. The chamber forming member has a hole 16 extending therethrough.

45 The wax pattern 10 is mounted upon the sprue pin 11, after which the latter is inserted in the hole 16 and held in position by a bit of wax or

other suitable material. The wax pattern is spaced from the end of the chamber former 13. The chamber former, sprue pin, etc., may be coated with oil to permit easy separation of the parts from the hardened investment. The pattern 10, sprue pin 11, chamber former 13, and the face of the shoulder 14 are coated with the investment material. The chamber former may then be placed flat on a surface with the pattern projecting upwardly and the flask 18 slipped over the same, the shoulder 14 centering the flask upon the chamber forming member. The flask 18 is a single cylindrical member which preferably tapers on the inside, thereby aiding removal of the investment 21 after it has hardened therein and the casting has been made. The flask 18 in Figure 1 is a split type of flask and the chamber forming member 12 is adapted for use with either style of flask. After the investment has hardened, heat is applied to soften the wax which holds the sprue pin in place, whereupon the sprue pin 11 is removed which leaves a sprue in the investment extending from the end of the chamber former 13 to the pattern 10. The chamber forming member 12 is then removed from the end of the flask which leaves a plastic receiving cavity or chamber 20 in the investment. The flask with the hardened investment is then heated which liquefies or vaporizes the wax of the pattern so that it is removed from the investment. A cavity or mold formed within the investment remains which is clear of all wax and conforms accurately with the wax pattern.

In the illustrated embodiment, the plastic chamber is formed in the investment. The plastic chamber is therefore carried by or associated with the flask, but it is not essential that the plastic receiving cavity or chamber be formed in the investment. In other words, the plastic chamber is disassociated from the piston or piston means excepting at the time when the piston is projected into the chamber to force viscous plastic into the mold formed in the investment.

The apparatus or machine for casting a dental restoration, using plastic as the casting material, includes a frame 23 having side members 24. The frame 23 carries a yieldable platform or platform means 25 which has a recess 26 at each end thereof. Each recess receives a side member 24 and the platform is retained thereby in position within the frame yet movable longitudinally with respect thereto. The platform 25 is impelled upwardly by spring means, four springs 27 being illustrated for impelling the platform upwardly. Each spring may be centered upon a projection 28 carried by the underside of the platform. A limiting screw 29 is secured to the platform 25 and the head thereof slides in a hole 30 which retains the platform on the frame yet permits relative vertical movement thereof.

The upper end of the frame carries a pressure means, such as a screw 33, upon the end of which is carried a piston 34. The piston preferably is rotatably mounted upon the end of the screw in any suitable manner, such as shown in Figure 6. The piston 34 is hollow to receive the head of a screw 35 which is threaded into the end of the screw 33. A ballbearing 36 is positioned between the end of the screw 33 and the piston 34 in order to permit free rotation of the piston upon the end of the screw. A plug 37 seals the end of the piston.

In the apparatus particularly illustrated, the platform means is resiliently mounted and the piston is carried by the pressure or screw means.

It is not essential that a resilient mounting be provided, although such mounting retains substantially uniform pressure upon the plastic while the latter is setting or hardening and the uniform pressure is obtained regardless of whether it is the platform means or the piston means which is resiliently or yieldably mounted. Similarly, any means is contemplated to obtain relative movement between the platform means and the piston means and it is immaterial which one of these means is propelled towards the other.

The flask, which is particularly illustrated within the apparatus or machine of Figure 1, is a two-part flask including a drag 41 and a cope 42. The cope and drag are secured together in any suitable manner such as by the bolts 43. Such a split flask is used whenever it is necessary to obtain more than one color in the finished product, such as by hand packing of two or more colors, by inserting a part or parts of a different color into the mold and the like.

This two-part flask shows a mold or cavity 45 which remains after the wax pattern has been melted or vaporized out of the investment. The mold or cavity is connected by a sprue 46, which was formed by the sprue pin 11, to the chamber 20. This chamber was formed by the chamber former 13 of the chamber forming member 12. The chamber 20 corresponds closely with the dimensions of the piston 34, allowing, however, for normal clearance. It has been found that a two-thousandths tolerance is satisfactory between the diameter of the piston and the inside diameter of the chamber. The tolerance may be greater than that enumerated, the only requirement being that the tolerance be not so great that effective pressure will be lost or that the plastic will pass between the piston and chamber walls and not into the mold when the piston is projected into the chamber against the viscous plastic therein while the latter is being pressed into the mold 45 and held pressed therein.

With the flask positioned upon the platform 25, the viscous plastic is placed in the chamber 20, whereupon the screw 33 is rotated to bring the piston down into the chamber 20 and pressure is applied to the plastic by continued rotation of the screw 33. This pressure forces the soft, viscous plastic into the mold 45. As the pressure increases, the platform 25 descends under the resistance of the springs 27, which springs retain the pressure upon the plastic. When sufficient pressure has been applied, the entire apparatus is placed in a hot bath, oven, furnace, or the like, whereupon the plastic hardens or sets while pressure is retained thereupon under the combined action of the upward pressure exerted upon the platform by the springs 27 and the screw 33 which presses the piston into the chamber 20.

The plastic chamber former 12 is an article of manufacture which enters into the method of casting, although it is not directly a part of the casting machine. It is, however, a necessary adjunct thereto since some means is required to provide a plastic chamber to be associated with or carried by the flask. The forming of a plastic chamber or cylinder in the investment is particularly advantageous because the excess plastic hardens in the investment or a destructible part and hence need not be cleaned or removed as would be the case if a permanent cylinder or chamber were provided. The chamber former also provides means for supporting the pattern

in proper position within the soft investment until it hardens.

This invention is presented to fill a need for improvements in an apparatus and method for casting dental restorations. It is understood that various modifications in structure, as well as changes in mode of operation, assembly, and manner of use, may and often do occur to those skilled in the art, especially after benefiting from the teachings of an invention. Hence, it will be understood that this disclosure is illustrative of preferred means of embodying the invention in useful form by explaining the construction, operation and advantages thereof.

What is claimed is:

1. An apparatus for casting dental restorations comprising a flask, an investment within the flask and having a mold and a plastic chamber formed therein, a frame, a platform means carried by the frame to receive the flask, a piston means carried by the frame and fitting the plastic chamber, and means to propel one of the aforesaid means towards the other whereby the piston moves into engagement with the plastic chamber and continues movement therewithin to apply pressure to the plastic therein.

2. An apparatus for casting dental restorations comprising a flask having an investment therein in which a mold is formed, a plastic receiving cavity associated with the flask, a frame, a platform means carried by the frame to receive the flask, a piston means carried by the frame and fitting the plastic chamber, a yieldable mounting for one of said means, and means to propel one of the aforesaid means towards the other so that the piston means enters the plastic chamber whereby the piston means applies pressure to the plastic within the plastic chamber and substantially uniform pressure is retained thereupon.

3. An apparatus for casting dental restorations comprising a flask, an investment within the flask and having a mold and a plastic receiving cavity formed therein, a frame, a platform means carried by the frame to receive the flask, a piston means carried by the frame and fitting the plastic chamber, a yieldable mounting for one of said means, and means to propel one of the aforesaid means towards the other so that the piston means enters and moves within the plastic chamber whereby pressure is applied and retained upon the plastic.

4. An apparatus for casting dental restorations in a mold formed in an investment provided within a flask which has a plastic chamber associated therewith comprising a frame, a platform means carried by the frame to receive the flask, a piston means carried by the frame and fitting the plastic chamber, a yieldable mounting for one of said means, and means to propel one of the aforesaid means towards the other whereby the piston means may be moved within the plastic chamber and substantially uniform pressure is retained upon the plastic.

5. An apparatus for casting dental restorations in a mold formed in an investment provided within a flask which has a plastic chamber associated therewith comprising a frame, a platform carried by the frame to receive the flask, a piston carried by the frame and fitting the plastic chamber, and means to propel the piston towards the platform whereby the piston moves within the plastic chamber and substantially uniform pressure is retained upon the plastic.

6. An apparatus for casting dental restorations in a mold formed in an investment provided within a flask which has a plastic chamber associated therewith comprising a frame, a platform carried by the frame to receive the flask, a yieldable mounting for the platform, a screw carried by the frame and directed towards the platform, and a piston carried by the screw and fitting the plastic chamber, the screw propelling the piston towards the platform whereby the piston moves within the plastic chamber and substantially uniform pressure is retained upon the plastic.

7. An apparatus for casting dental restorations in a mold formed in an investment provided within a flask which has a plastic chamber associated therewith comprising a frame having side members, a platform to receive the flask and slideable along the side members of the frame, a yieldable mounting for the platform, a screw carried by the frame and directed towards the platform, a piston carried upon the end of the screw and fitting the plastic chamber, the screw propelling the piston towards the platform whereby the piston moves within the plastic chamber and the yieldable platform retains substantially uniform pressure upon the plastic.

8. An apparatus for casting dental restorations comprising a flask adapted to receive a soft investment therein, a cavity former carrying a wax pattern for insertion into the soft investment until the latter hardens to form a mold and a plastic receiving cavity in the hardened investment, a frame, platform means carried by the frame to receive the flask, piston means carried by the frame and fitting the plastic chamber, and means to propel one of the aforesaid means towards the other whereby the piston means moves into and within the plastic chamber and applies pressure to the plastic therein.

9. An apparatus for casting dental restorations comprising a flask adapted to have a soft investment therein, a cavity forming member having means to align the same with the flask and having a cavity former carrying a wax pattern for insertion into the soft investment until the latter hardens to form a mold and a plastic receiving cavity in the hardened investment, a frame, platform means carried by the frame to receive the flask, piston means carried by the frame and fitting the plastic chamber, and means to propel one of the aforesaid means towards the other whereby the piston means moves into and within the plastic chamber and applies pressure to the plastic therein.

10. An apparatus for casting dental restorations comprising a flask adapted to have a soft investment therein; a cavity forming member having a plastic receiving cavity former with a hole extending therethrough, a sprue pin projecting from the hole, and a wax pattern upon the end of the sprue pin, the chamber former, projecting sprue pin and pattern adapted to be inserted into the soft investment until the latter hardens to form a mold, a plastic chamber and a connecting sprue hole; a frame; platform means carried by the frame to receive the flask; piston means carried by the frame and fitting the plastic chamber; and means to propel one of the aforesaid means towards the other whereby the piston means is adapted to move into and within the plastic chamber and apply pressure to the plastic therein.
